TRAY FOR FRUIT

Champlyn Kenneth Sulger, 11650 Loyola Drive, and John F. Pandolfo, 23467 Esberg Road, both of Los Altos, Calif. 94022

Filed June 21, 1965, Ser. No. 85,838

Term of patent 14 years

(Cl. D58—13)

FIG. 2

FIG. 1

FIG. 4

FIG. 3

FIG. 5

FIGURE 4 is an end elevational view thereof the end opposite being identical thereto; and

We claim:

The ornamental design for a tray for fruit, substantially as shown and described.
